FIG. 1 is a perspective view of the front and one side of a sword showing my new design;

FIG. 2 is a rear elevational view thereof;

FIG. 3 is a side elevational view thereof;

FIG. 4 is a top plan view thereof; and

FIG. 5 is an enlarged perspective view thereof, the blade being fragmentarily shown for convenience of illustration.

The characteristic features of my design reside in the specific configuration of the combined hand grip and crossguard.

I claim:

The ornamental design for a sword, as shown and described.
